UNITED STATES PATENT OFFICE.

CHARLES H. BROWNE, OF JACKSON, MICHIGAN.

PRESS FOR PACKING BRAN, &c.

SPECIFICATION forming part of Letters Patent No. 357,814, dated February 15, 1887.

Application filed March 15, 1886. Serial No. 195,244. (No model.)

To all whom it may concern:

Be it known that I, CHARLES H. BROWNE, of Jackson, in the county of Jackson and State of Michigan, have invented new and useful 5 Improvements in Presses for Packing Bran, &c., of which the following is a specification.

This invention relates to an improvement in that class of presses which are composed of a jointed pressing-case into which the material 10 is compressed from the receiving case or chamber by a follower which is actuated by a screw.

The object of my invention is to construct a press of this character which is suitable for 15 pressing or packing bran and other similar material, and which is easily manipulated and actuated with a comparatively small expenditure of power.

My invention consists, to that end, of the improvements which will be hereinafter fully set 20 forth, and pointed out in the claims.

In the accompanying drawings, consisting 25 of two sheets, Figure 1 is a sectional front elevation of my improved press. Fig. 2 is a sectional side elevation of the same. Fig. 3 is a top plan view of the same. Fig. 4 is a horizontal section in line $x-x$, Fig. 1. Fig. 5 is a vertical section of the pressing-case on an enlarged scale. Fig. 6 is a vertical section of the upper portion of the pressing-case in line 30 $y-y$, Fig. 5, on an enlarged scale. Fig. 7 is a horizontal section in line $z-z$, Fig. 5. Fig. 8 is a top plan view of the bottom frame of the pressing-case. Fig. 9 is a fragmentary sectional side elevation of the upper receiving-case and cross-head. Fig. 10 is a vertical section of the upper cross-head and receiving-case. Fig. 11 shows one of the spring-catches reversed.

Like letters of reference refer to like parts 40 in the several figures.

A represents the stationary main frame of the machine; B, the jointed pressing-case, which can be removed from the machine and opened for withdrawing the pressed block of 45 bran or other material.

C and D represent, respectively, the upper and lower receiving-cases, from which the material is compressed into the case B by the followers E and F.

50 a represents the horizontal driving-shaft provided with the necessary tight and loose pulleys a' for turning the shaft in either direction, or stopping it, as may be desired. The

shaft a is journaled in suitable bearings secured to the top portion of the main frame. 55

b is a horizontal counter-shaft, which receives motion from the driving-shaft a by gear-wheels b' b^2 , and which transmits motion to a horizontal counter-shaft, c , by gear-wheels c' c^2 . The shaft c is arranged in line with the driving-shaft a , and carries a pinion, c^3 , which meshes with two gear-wheels, c^4 . The latter are secured to horizontal counter-shafts d , arranged on opposite sides of the counter-shaft c , and carry bevel gear-wheels d' . 60

$f f$ represent two vertical screw-shafts arranged on opposite sides of the receiving-cases C and D, and journaled in bearings f' at the top of the frame A, and in steps f^2 at the bottom of said frame. The screw-shafts $f f$ are 65 provided at their upper ends with horizontal bevel-wheels g , which are driven by the bevel-wheels d' . The screw-shafts f work in threaded openings or nuts in the followers E and F, and each shaft is provided with a right-and-left 70 screw, so that the followers are moved by the screw-shafts in opposite directions. The screw-shafts are preferably supported near their middle in bearings f^3 , secured to the front posts of the frame A. 75

The receiving-cases C and D and the pressing-case B are preferably made square in cross-section. The upper receiving-case, C, is rigidly secured to the frame A, so as to be stationary, while the lower receiving-case, D, 80 and the pressing-case B are made vertically movable, so that they can be lowered from the upper case, C, when the operation of pressing is completed. The side walls of the receiving-cases C and D are provided with vertical 85 slots h h' , through which the arms h^2 h^3 of the followers E and F move. These slots are closed by movable covers H H' , fitted against the outer sides of the cases C and D and sliding in horizontal ways h^4 h^5 . The sliding covers H 90 H' are pressed against the followers by springs h^6 h^7 , and the contiguous sides of the follower-arms h^2 h^3 and covers H H' are made inclined, so that the follower-arms will press these covers backward and out of the way as the followers move toward the pressing-case B, while the springs h^6 h^7 will return the covers to their former positions as the followers move away from the pressing-case. 95

I represents the feed-spout, through which 100 the bran or other material to be pressed is de-

livered into the upper end of the upper receiving-case, C. The upper follower, E, is provided with a suitable opening, i , through which the material passes into the case C.

5 E' represents the removable follower-board, which is applied to the under side of the follower E. This board is removed and applied through an opening, i' , formed in the front of the case C and provided with a sliding cover, i^2 .

10 F' represents a similar removable board applied to the lower follower, F.

The pressing-case B is open at the top and the bottom, and composed of four side walls hinged together at j j' j^2 and a bottom frame, J. The 15 side walls are locked together by a series of cams, k, which are secured to a vertical rod, k' , and which engage against ribs k^2 and force the latter against stops k^3 . The rod k' is turned by a hand-lever, K. The side walls of 20 the pressing-case are preferably perforated and lined with coarse wire-cloth k^4 , which permits of the escape of the air from the bran and prevents the sack from slipping in the pressing-case during the operation of compressing 25 the bran.

25 L represents spring bolts or catches attached to the upper and lower ends of two of the side walls of the pressing-case B, on opposite sides thereof, for the purpose of locking the follower-boards against the block or package of bran in the case B when the pressing is completed. The ends of the bolts L are beveled to permit the follower-boards E' F' to press the bolts back as the boards enter the pressing-case B. When the pressing is completed, the follower-boards have passed the bolts L and the latter are projected by their springs, as represented in Fig. 6. The pressing mechanism is so timed that the follower-boards are 40 forced into the case B a short distance beyond the catches L, so that when the pressure is removed, the reaction of the compressed material will take place in the case B and force the follower-boards back against the catches, 45 thereby preventing the compressed material from expanding after it is removed from the case B, which would result in a change of form and size in the compressed block or package.

The follower-boards E' F' are covered with 50 sacking when they are introduced into the receiving-cases C and D. After the material is pressed the bolts L are turned by means of the hand-levers l, with which they are provided, so that there beveled or inclined faces are reversed, which permits the ready removal of the follower-boards.

The bottom frame, J, of the pressing-case B is provided with rollers m, which are adapted to run on rails m' when the case B is lowered, 60 thereby affording ready means for moving the case B to and from the receiving-case C.

The lower receiving-case, D, has a limited vertical movement in the frame A, and is provided for that purpose with vertical slots n, 65 through which pass headed studs n', which are secured to the frame A.

The lower end of the case D is provided with

a bridge-tree, o, which rests upon the front end of a lever, o'. The latter is pivoted to the lower portion of the frame A, and is provided at its rear end with a weight, o², which counterbalances the weight of the cases B and D and connecting parts, which rest upon the lever o'. 70

o³ is a vertical shifting-rod, which is attached to the rear end of the lever o', and provided with a nose, o⁴, which bears against the stop o⁵ on the frame A when the cases B and D are elevated. 75

P is an arm which projects rearwardly from the lower follower, F. This arm strikes against the nose o⁴ of the shifting-rod o³ when the pressing is completed, thereby releasing the shifting-rod and permitting the cases B and D with the compressed package to descend until the rollers of the case B rest upon the rails m'. 85 The shifting-rod o³ is provided with a projection or treadle, o⁶, for depressing the rod and elevating the cases B and D.

Q is a spring or elastic buffer, which is secured to the bridge-tree o, and which strikes 90 against the lower portion of the frame A when the case D descends, thereby arresting the downward movement of the case gradually.

R represents a plate arranged upon the lower follower, F, and supporting the lower follower-board, F'. The lower case, D, may be provided with an opening, r, protected by a slide, r', through which opening the board F' may be inserted and removed. The plate R is provided with a downwardly-extending stem, s, 100 which is guided in an opening in the follower F, and rests upon the front end of a lever, S. The latter is pivoted to the lower end of a vertical rod, t, which is connected with its upper end to a scale-beam, T. 105

u is a vertical rod attached with its lower end to the rear end of the lever S, and provided near its upper end with a nose, u', which engages under a fixed stop, u². The upper end of the rod u is provided with a treadle, u³. Upon depressing the rod u the plate R is lifted from the follower F, whereby the plate and the board F' resting thereon are caused to support the material in the cases B, C, and D. In this position of the parts the weight of the material is indicated by the scale-beam T, and when the proper quantity has been introduced into these cases the supply is shut off. Upon disengaging the rod u from the stop u² the plate R descends and rests upon the follower F, 115 thereby rendering the weighing contrivance inoperative. 120

When the cases B and D are elevated, as represented in Figs. 1 and 2, the press is ready to receive the material. The material passes 125 into the cases D, B, and C from the spout I, and when the desired quantity has been received the supply is shut off and the upper follower-board is introduced into the upper case, C. The screw-shafts f are now set in motion, whereby the followers E and F are moved toward the pressing-case B, forcing the material from both receiving-cases C and D into the pressing-case B. When the operation of 130

pressing is completed, the actuating mechanism is arrested and reversed by a shipper-rod, v , which is moved by an arm, v' , on the upper follower, E. By reversing the motion of the screw-shafts the pressure is removed from the followers, and then the pressing-case B is permitted to rest upon the rails. The shifting-rod o^3 is at the same time disengaged from the stop o^5 , thereby permitting the lower case, D, and the pressing-case B to descend. The followers E and F are locked against the upper and lower sides of the package of compressed material in the case B by the spring-catches L. The case B is now run out on the rails m' , opened, and the package removed. A sack or bag is again placed in the case B, the latter returned under the upper case, C, and the lower case, D, and case B are elevated by depressing the rod o^3 . The followers are returned to their former position by reversing the motion of the actuating mechanism and the operation is repeated. In this manner a powerful pressure is applied to the material from both ends of the chambers in which the material is contained, and as no bending of the screw-shafts is liable to occur these shafts and the connecting parts can be made comparatively light without sacrificing safety. The power required for effecting the compression is comparatively small, and the machine is operated with great speed and convenience.

I claim as my invention—

1. In a press, the combination, with two receiving-cases, of an intermediate movable pressing-case capable of being placed in communication with both receiving-cases, and adapted to be removed therefrom for discharging the compressed package, and followers moving in the receiving-cases toward and from the intermediate pressing-case, substantially as set forth.

2. The combination, with a stationary receiving-case, C, of a movable receiving-case, D, a movable pressing-case, B, and followers E F arranged in the receiving-cases, substantially as set forth.

3. The combination, with an upper stationary receiving-case, C, of a lower receiving-case, D, capable of vertical movement, a pressing-case, B, resting on the lower case, D, and capable of lateral movement toward and from the receiving-cases, and followers E F arranged in the receiving-cases, substantially as set forth.

4. The combination, with an upper stationary receiving-case, C, of a lower receiving-case, D, capable of vertical movement, a pressing-case, B, provided with rollers m , and rails m' , upon which the rollers m run when the pressing-case is lowered, substantially as set forth.

5. The combination, with an upper receiving-case, C, a lower receiving-case, D, and an intermediate pressing-case, B, of followers E F, arranged in the receiving-cases C and D, and screw-shafts f , arranged on opposite sides

of said cases and connected with said followers, substantially as set forth.

6. The combination, with the receiving-cases C and D, provided with followers E F 70 and loose follower-boards E' F', of an intermediate pressing-case, B, provided at both ends with spring-catches L, whereby the follower-boards are locked in position when the pressing is completed, substantially as set 75 forth.

7. The combination, with the pressing-case, of a receiving-case provided with vertical slots h , a follower having its arms arranged in said slots, and movable covers H, whereby said 80 slots are opened and closed as the follower-arms move through said slots, substantially as set forth.

8. The combination, with the pressing-case, of a receiving-case provided with vertical slots h , a follower having arms provided with inclined faces, sliding covers H, constructed with similar inclined faces, and springs whereby the sliding covers are held against the follower-arms, substantially as set forth. 90

9. The combination, with the receiving-case C, provided with an opening, i' , of a follower, E, and a detachable follower-board, E', substantially as set forth.

10. A pressing-case having perforated side 95 walls covered on their inner sides with reticulated material whereby the bag is held against slipping, substantially as set forth.

11. The combination, with the lower receiving-case, D, of a supporting-lever, o' , shifting-rod o^3 , provided with stop o^4 , a stop, o^5 , 100 and a follower provided with an arm, P, substantially as set forth.

12. The combination, with the pressing-case and the receiving-case D, of a follower, 105 F, mechanism, substantially as described, whereby the follower is raised and lowered, a plate, R, made movable independent of the follower, and a scale connected with the plate R, substantially as set forth. 110

13. The combination, with the receiving-case D, of the follower F, mechanism, substantially as described, whereby the follower is raised and lowered, a plate, R, made movable independent of said follower, a lever, S, 115 which supports the plate R, and a scale-beam, T, connected with the lever S, substantially as set forth.

14. The combination, with the receiving-case D, of a follower, F, a plate, R, made 120 movable independent of said follower, a lever, S, which supports the plate R, a scale-beam, T, connected with the lever S, a rod, u , attached to the lever S, and provided with a nose, u' , and a stop, u^2 , substantially as set 125 forth.

Witness my hand this 2d day of March, 1886.

CHARLES H. BROWNE.
